CLAIM

The ornamental design for an undershirt, as shown and described.

DESCRIPTION

FIG. 1 is a front view of a first embodiment of my new design for a crew neck undershirt, the undershirt shown in broken lines to indicate the environment of the claimed portion of the undershirt, and the design having a message, "Looking Good" centered and vertically oriented on the front surface of the undershirt and followed by a logo graphic disposed below the message, wherein the claimed portion is bounded by a rectangle distinguishable by a dot-dash patterned broken line, and all broken lines depicted in FIG. 1 form no part of the claimed design; and, FIG. 2 is a front view of a second embodiment of my new design for a v-neck undershirt, the undershirt shown in broken lines to indicate the environment of the claimed portion of the undershirt, and the design having a message, "Looking Good" centered and vertically oriented on the front surface of the undershirt and followed by a logo graphic disposed below the message, wherein the claimed portion is bounded by a rectangle distinguishable by a dot-dash patterned broken line, and all broken lines depicted in FIG. 2 form no part of the claimed design.

All broken lines in the drawings form no part of the claimed design.
